GAS FIRED WATER HEATER

George W. Myler, 1487 Langston Drive,
Columbus, Ohio 43220

Filed Feb. 3, 1970, Ser. No. 21,226

Term of patent 14 years

Int. Cl. D23—03

U.S. Cl. D23—86

Fig. 1

Fig. 2

Fig. 3

FIG. 1 is a front perspective view of a gas fired water heater embodying my design.

FIG. 2 is a rear perspective view thereof.

FIG. 3 is a fragmentary perspective view thereof, the duct being shown in broken lines for illustrative purposes only.

I claim:

The ornamental design for gas fired water heater, as shown and described.
